UNITED STATES PATENT OFFICE.

FRED THOMAS ROBERTS, OF UPPER MONTCLAIR, NEW JERSEY, ASSIGNOR TO PARAMOUNT RUBBER CONSOLIDATED, INC., OF PHILADELPHIA, PENNSYLVANIA, A CORPORATION OF DELAWARE.

METHOD AND APPARATUS FOR MAKING JARS OF HARD RUBBER AND SIMILAR MATERIALS.

Application filed April 10, 1922. Serial No. 551,279.

To all whom it may concern:

Be it known that I, FRED THOMAS ROBERTS, a citizen of the United States, residing at Upper Montclair, in the county of Passaic and State of New Jersey, have invented a certain new and useful Improvement in Methods and Apparatus for Making Jars of Hard Rubber and Similar Materials, of which the following is a full, clear, and exact description, reference being had to the accompanying drawings.

The object of this invention is to provide for the rapid and economical manufacture of rubber jars, particularly jars of hard rubber, for instance such as may be used for batteries.

In carrying out my method, I take two sheets of rubber stock suitable for vulcanization and pneumatically seat them, in trough form, in two co-operating molds. I then place in one of the seated rubber troughs members adapted to form the bottoms of a plurality of jars. I then bring the mold members into conjunction to form a closed article, some heat expanding material being placed within the article before joining. I then vulcanize the article as a closed member and thereafter sever it to provide a plurality of open ended jars of which the inserted members constitute the bottoms.

In carrying out my process in the preferred manner, I use at the opposite ends of one of the troughs of seated rubber inwardly facing bottom members for jars, and I locate, intermediate of such members, one or more double faced bottom members. Then after vulcanization, I cut through the double faced bottom members to form a plurality of double units and I then sever these units so that each forms a pair of open ended jars.

In carrying out my process, I prefer to use sheets of rubber which are raw, while I use as the bottom members blocks which are cured only sufficiently to make them hold their shapes and which are of such composition that they require for the completion of their vulcanization substantially the same degree and time of heating as is required by the raw rubber sheets. In making battery jars, the composition of both the sheets and the bottoms is such as to vulcanize into hard rubber, and the bottoms in this case

are preferably provided with internal projecting ribs.

My invention is illustrated in the drawings hereof, and is hereinafter more fully explained in connection with these drawings, and the essential novel features are summarized in the claims.

Fig. 1 is a perspective of the upper and lower molds, which are duplicates and are used for forming the uncured multiple article; Fig. 2 is a sectional perspective of the lower forming mold; Fig. 3 is a cross section of the upper and lower forming molds, with the rubber sheets as originally positioned thereon; Fig. 4 is a similar view with the rubber sheets seated by suction; Fig. 5 is a perspective of a semi-cured rubber insert which constitutes the bottoms of adjacent finished articles; Fig. 6 is a plan of the lower mold with the bottom inserts and end shearing devices placed therein; Fig. 7 is a perspective of one of the end shearing device; Fig. 8 is a vertical section of forming molds similar to Figs. 3 and 4 after they have had all the parts placed therein and have been brought together; Fig. 9 is a fragmentary plan, on an enlarged scale, illustrating the end shearing device in conjunction with one of the end bottom members and a seated rubber wall; Fig. 10 is an enlarged fragmentary vertical section through two of the coacting forming mold members; Fig. 11 is an enlarged inner end view of the shearing device shown in Fig. 7; Fig. 12 is a perspective of an uncured multiple article produced by the molds and members of the preceding figures; Fig. 13 is a vertical transverse section through two coacting vulcanized molds for the multiple article; Fig. 14 is a perspective of the completely cured article before severance thereof; Fig. 15 is a perspective of the cured article severed into a plurality of duplex articles; Fig. 16 is a perspective of one of the duplex articles severed into two units, and Fig. 17 is a larger perspective of one of the units, illustrating the final product of the operation.

In Figs. 1 to 4, inclusive, 10 indicates either of the pair of molds, each having a pair of parallel upstanding ribs 11 leaving a flat space 12 between them. The ribs 11 are cut off diagonally at their extreme ends,

as illustrated at 13 for a purpose hereinafter described. Within the base portion of the molds are channels 14 which communicate by passageways 15 with the open ended 5 channel provided by the ribs and intervening mold space. In the face of each mold member outside of the rib, I provide a circuitous channel 16, which, by means of 10 passageways 17, is in communication with the channel 14. Suitable means, indicated by the pipe 18, are provided for exhausting the air from the channel 14, and hence from the space between the ribs and from the surrounding channel 16.

15 With such an apparatus as described, I place two sheets of rubber stock (indicated by A in Fig. 3) across the faces of the molds, and I then exhaust the air from the channels and space of the mold, either by means 20 of suction through the pipe 18, or by a pressure higher than atmospheric caused to act on the face of the sheets opposite the mold cavities, as for instance, by placing the molds within an atmosphere of compressed 25 air, while the pipe 18 leads to the outside, or placing an open faced compressed air chest between the molds. In either case, I cause the air pressure within the mold cavities to be lower than that outside the cavities, 30 whereupon such superior external pressure seats the rubber stock, as indicated at A' in Fig. 4.

When the stock is seated it lies snugly 35 against the face 12 of the mold and over the ribs and passes down over the ends 13 of the ribs, which, as heretofore stated, are cut off diagonally, such diagonal cutting being for the purpose of enabling the stock to readily approach the broad face of the 40 molds. The sheet of rubber is bound to the mold entirely around the ribs by reason of being pneumatically forced into the clamping groove 16.

When the stock has been seated as described, I place in each end portion a suitable end shearing device; one form of such device is shown in Fig. 7. In this figure, 20 indicates a suitable block having dowel pins 21 adapted to co-operate with holes 22 (Fig. 50 2) in the mold. On the inner end of this block are four shearing strips 24, 25, 26, 26 arranged to form an open rectangular frame, as shown in Fig. 11, and having inclined abutting edges 27. Suitable means, as 55 leaf springs 28, hold these frame members in the approximate position shown in Fig. 11 but allow movement thereof.

When the shearing devices are in position the end members 26 of the frame abut the 60 vertical walls, a^1 , Fig. 4, of the seated rubber stock, the bottom member 24 rests on the flat surface a^2 of such stock and the top member 25 stands somewhat higher than the distance between the flat surfaces a^2 when 65 the mold members are brought together.

I now place within the lined trough-shaped cavity adjacent to the end closures, rubber bottom blocks 30 which have flat faces 31 resting against the face of the marginal members 24, 25 and 26 and have integral ribs 32 extending inwardly therefrom.

If the apparatus is designed for making only two jars at a time, I can proceed to 75 close the molds after placing the end bottom blocks in the two shearing members 20. However, I consider it preferable to have the apparatus make several jars at once, and, to that end, I place intermediately in the lined cavity, one or more double faced bottom members, illustrated at 35 in Figs. 5 and 6. Each of these double faced bottom members has an intermediate portion 37 slightly more than twice the thickness of the bottom proper of the jar and suitable integral ribs 85 38 on opposite sides thereof.

Fig. 6 shows particularly the apparatus as used in making four battery jars at a time, and in that case I use but one of the double bottom members, though the number of these may be increased as desired.

90 Following the placing of the bottom members, I put in each of the cavities between the respective bottom members, a suitable heat expanding substance, as water or carbonate of ammonia, for instance. Then I bring the two mold members together. In this operation the edges of the ribs 11 come into coaction and join the overlying rubber into a seam and at the same time shear it off, as illustrated in Fig. 10. This same pressure of the mold members toward each other causes the horizontal cutting members 24 and 25 to press against the horizontal flat portions of the seated stock, so that these members not only shear through the stock but are bodily forced toward each other by the approaching molds, and this movement, by reason of the inclined end engagement 27, 95 forces outwardly the vertical members 26 which shear the sides of the stock.

100 The result of the above described operation is that I have produced a completely closed article joined by pressure seams and the surplus stock has been sheared off. On separation of the molds, this closed article, which is illustrated in Fig. 12, is then removed and transferred to a suitable vulcanizing mold. In this view, A^2 designates the raw rubber walls of the article; a^3 the longitudinal seam thereof, and 30 and 35 the comparatively stiff bottom members.

105 A vulcanizing mold is illustrated, for instance, in Fig. 13, and comprises two mold members 40 each having a rectangular cavity therein of half the size of the article. A small vent 41 leads from each cavity to the exterior to allow the escape of air. I have shown the vulcanizing mold as made of hollow members 40 to provide spaces 42 into 110

which steam may be admitted through pipes 43 to supply the vulcanizing heat. When such heat is supplied the substance within the article expands and furnishes the required internal pressure to insure proper vulcanization.

After vulcanization the molds are separated and the article appearing as A³ in Fig. 14 is removed therefrom. This article is now 10 sawed apart through the center of each of the double bottom members 35 and midway between adjacent bottom members. To indicate the desired location of the said kerfs, I preferably form slight ribs around the interior of the vulcanizing mold to cause slight grooves or marks on the vulcanized article, as indicated at a⁴, a⁵ a⁶ in this figure.

In the particular illustration given, only 20 one of the double bottom members is employed, and sawing this member apart at a⁴ produces two double articles, as shown at A⁴ A⁴ in Fig. 15. Each of these double articles when sawed apart at a⁵ producing the pair of jars shown as A⁵ A⁵ in Fig. 16; one of 25 these jars appearing as the final unit A⁶ in Fig. 17.

It will be seen that my method is simple, as is adapted for producing rubber jars with great rapidity and economy.

30 I claim:—

1. The method of making jars consisting of seating stock in suitable mold members, applying oppositely facing stock thereto to form a plurality of jar bottoms, joining such stock to other stock to form a closed article, curing the article while closed, and thereafter severing it to produce a plurality of open-ended jars.

2. The method of making jars of rubber 40 or similar material, consisting of pneumatically seating stock in suitable mold members, applying rubber stock thereto to form a jar bottom with upstanding ribs, joining such stock to other stock to form a closed article, vulcanizing the article while closed, and thereafter severing it.

3. The method of making jars of rubber or similar material, consisting of placing stock on suitable mold members, seating the 50 same by suction, applying other stock thereto to form a plurality of jar bottoms, forming a closed article by bringing the mold members together, vulcanizing the article while closed, and severing it between bottoms to produce a plurality of open-ended jars.

4. The method of making hard rubber jars consisting of pneumatically seating raw rubber stock in suitable mold members, applying partially cured stock thereto to form 60 jar bottoms, forming a closed article by bringing the mold members together, vulcanizing the article as a unit while closed, and severing it between bottoms.

5. The method of making hard rubber

jars comprising seating sheet stock in two mold members, each member having a cavity corresponding to longitudinally divided halves of a plurality of jars end to end, inserting bottom members, bringing the mold 70 members together to form a complete unit, vulcanizing the unit in this condition until it is hard, and finally severing it to make a plurality of jars.

6. The method of making hard rubber 75 jars comprising seating sheet stock by suction in two mold members, each member having a cavity corresponding to longitudinally divided halves of a plurality of jars end to end, inserting ribbed members in one 80 of the lined cavities, inserting heat expanding material, bringing the mold members together to form a complete unit, vulcanizing the unit by heat in this closed condition to make a hard rubber article, and finally sawing 85 it apart between ribbed members.

7. The method of making jars, consisting of seating in the cavities of a pair of molds, raw rubber sheet stock of a composition suitable for vulcanization into hard rubber, applying partially cured rubber blocks to the seated stock adjacent to the two ends thereof, bringing the two mold members together under pressure to form a completely closed article and at the same time shearing off the 90 surrounding stock, vulcanizing the closed article to make a unitary hard member, and thereafter severing it transversely to make a 95 plurality of jars.

8. The method of making jars, consisting 100 of seating in rectangular cavities of a pair of molds, raw rubber sheet stock of a composition suitable for vulcanization into hard rubber, each cavity having a cutting edge, applying partly cured rubber blocks to the seated stock adjacent to the two ends thereof, inserting heat expanding material, bringing the two mold members together to form a completely closed article and at the same time shearing off the surrounding stock, then 105 transferring the closed article to another mold and vulcanizing it as a closed article, and thereafter sawing it transversely to make hard rubber jars.

9. The method of making jars consisting 110 of seating in rectangular cavities of a pair of molds, sheet stock of a composition suitable for vulcanization into hard rubber, each cavity having a cutting edge, applying rubber blocks suitable for vulcanization into 115 hard rubber to the seated stock adjacent to the two ends thereof, bringing the two mold members together to form a completely closed article without an internal mandrel and at the same time shearing off the surrounding stock, then transferring the closed article to another mold and vulcanizing it 120 as a closed article, and thereafter sawing it transversely to make a plurality of jars.

10. The method of making jars of rubber 125

- or similar material, consisting of pneumatically seating in mold members, stock for the body of the jars, placing on such seated stock in an intermediate location material to form the bottoms of two jars, bringing the mold members together to join the closed article and remove the surplus stock, vulcanizing the article while closed, and thereafter severing it.
11. The method of making jars of rubber or similar material, consisting of seating by suction in mold members, raw rubber stock for the body of the jars, placing on such seated stock in an intermediate region rubber to form the bottoms of two jars, bringing the mold members together to join the closed article and remove the surplus stock, vulcanizing the article while closed, and thereafter severing it in said intermediate region.
12. The method of making hard rubber battery jars, consisting of pneumatically seating in mold members, stock for the body of the jars, placing on such seated stock ribbed blocks to form the bottoms and internal ribs of the jars, bringing the mold members together to join the closed article and remove the surplus stock, vulcanizing the article while closed and with a suitably caused internal pressure, and thereafter sawing the article apart.
13. The method of making jars of rubber, comprising seating plastic stock in mold members, applying to the said seated stock in an intermediate location one or more double bottoms, bringing the mold members into conjunction to join the stock, vulcanizing the article, and severing it through the double bottoms.
14. The method of making jars of rubber, comprising seating plastic stock in mold members, applying to the said seated stock single bottoms adjacent to the ends of the seated stock, and one or more double bottoms intermediate of the single bottoms, bringing the mold members into conjunction to join the stock, vulcanizing the article, and severing it through the double bottoms and between such bottoms and the single bottoms.
15. The method of making jars of rubber, comprising pneumatically seating plastic stock in mold members, applying to such seated stock single bottoms adjacent to the ends of the seated stock, and one or more double bottoms intermediate of the ends, bringing the mold members into conjunction to join the stock, vulcanizing the article as a unit, and severing it through the double bottoms and between such bottoms and the single bottoms.
16. The method of making jars of hard rubber, comprising pneumatically seating plastic stock in mold members, applying to the said seated stock single bottoms adjacent to the ends of the seated stock, and one or more double bottoms intermediate of the ends, bringing the mold members into conjunction to join the stock, vulcanizing the article as a unit, and severing it through the double bottoms and between such bottoms and the single bottoms.
17. The method of making rubber jars, comprising seating plastic stock between ribs on a mold member, placing outwardly acting cutting devices in such seated stock adjacent the ends of such stock, bringing other stock into conjunction with the said seated stock to join it thereto to embrace suitably placed bottom members, vulcanizing the article, and severing it into a plurality of jars.
18. The method of making rubber jars, comprising pneumatically seating plastic stock between ribs on mold members, placing cutting devices adjacent the ends of such stock on one of the mold members, placing bottom members between the cutting devices, and bringing the mold members into conjunction, vulcanizing the article, and severing it into a plurality of jars.
19. The method of making rubber jars, comprising seating by suction plastic stock between ribs or mold members, placing cutting devices adjacent the ends of such stock on one of the mold members, placing bottom members against the inner faces of the cutting devices, bringing other stock into conjunction with the said seated stock and the bottom members, vulcanizing the article, and severing it into a plurality of jars.
20. The method of making hard rubber jars, comprising seating rubber stock between ribs or mold members, placing cutting devices adjacent the ends of such stock, placing rubber bottom members between the cutting devices, bringing other stock into conjunction with the said seated stock and the bottom members, vulcanizing the article to make a unitary hard rubber member, and severing it into a plurality of jars.
21. An apparatus for making jars comprising in combination a two part cavitary mold, means for pneumatically seating stock in the cavities of the mold, and a cutting device adapted to be seated within the lined cavities and cut outwardly in all directions when the two parts of the mold are brought together.
22. The process of making hard rubber battery jars and similar articles, consisting of seating by section in mold cavities raw rubber stock of a composition suitable for vulcanization into hard rubber, applying within the seated stock devices adapted to cut outwardly in all directions, applying suitable bottom members of a composition suitable for vulcanization into hard rubber, closing the article, vulcanizing the

article as a closed unit, and thereafter sawing it apart to make hard rubber jars.

23. The process of making jars, comprising taking a pair of mold members, each having a pair of parallel wall-forming surfaces, seating plastic stock against such surfaces and in contact with the space between them, then placing within the seated stock on one of the members devices which are provided with cutting edges adapted to cut both horizontally and vertically, then placing inwardly facing bottom members along the inner faces of such cutting devices, then bringing the seated stock in the other mold member into conjunction with the stock described in form seams.

24. The process of making jars, comprising taking a pair of mold members, each having a pair of parallel cutting ribs thereon, pneumatically seating plastic stock suitable for vulcanization across such ribs and in contact with the space between them, then placing within the seated stock on one of the members adjacent to the ends thereof devices which are provided with cutting edges adapted to cut both horizontally and vertically, then placing inwardly facing bottom members along the inner faces of such cutting devices, then bringing the seated stock in the other mold member into conjunction with the stock described to form seams and cut off the surplus stock by means of the ribs and cutting devices, vulcanizing the article and severing it.

25. The process of making jars, comprising taking a pair of mold members, each having a pair of parallel cutting ribs thereon, seating by suction raw rubber stock across such ribs and in contact with the space between them, then placing within the seated stock on one of the members adjacent to the ends thereof devices which are provided with cutting edges adapted to cut both horizontally and vertically, then placing inwardly facing bottom members along the inner faces of such cutting devices, then bringing the seated stock in the other mold member into conjunction with the stock described to form seams and cut off the surplus stock, then transferring the closed article produced to another mold and vulcanizing it therein, and thereafter severing the article between the bottoms.

26. The process of making jars of hard rubber, comprising taking a pair of mold members, each having a pair of parallel ribs thereon with vertical inner surfaces, pneumatically seating plastic stock suitable for vulcanization into hard rubber across such ribs and in contact with the horizontal space between them, then placing within the seated stock on one of the members adjacent to the ends thereof devices which are provided with cutting edges arranged in a rectangle and adapted to cut both horizon-

tally and vertically, then placing inwardly facing bottom members along the inner faces of such cutting devices, then bringing the seated stock in the other mold members into conjunction with the stock described to form seams and cut off the surplus stock, then transferring the closed article produced to another mold and vulcanizing it therein, and thereafter sawing the hard rubber article into parts between the bottoms.

27. The process of making jars, comprising taking a pair of mold members, each having a pair of parallel wall-forming surfaces seating plastic stock against such surfaces and in contact with the space between them, then placing within the seated stock on one of the members devices which are provided with cutting edges adapted to cut both horizontally and vertically, then placing inwardly facing bottom members along the inner faces of such cutting devices, placing within the seated stock one or more double bottom members, then bringing the seated stock in the other member into conjunction with the seated stock and bottoms and cutting edges, and eventually cutting the article into parts through the double bottoms and between the various bottoms.

28. The process of making jars, comprising taking a pair of mold members, each having a pair of parallel cutting ribs thereon, pneumatically seating plastic stock suitable for vulcanization across such ribs and in contact with the space between them, then placing within the seated stock in one of the members adjacent to the ends thereof devices which are provided with cutting edges adapted to cut both horizontally and vertically, then placing inwardly facing bottom members along the inner faces of such cutting devices, placing within the seated stock one or more double bottom members, then bringing the seated stock in the other member into conjunction with the seated stock and bottoms and cutting edges, then vulcanizing the article with the bottoms in place, and finally cutting the vulcanized article into parts through the double bottoms and between the various bottoms to produce a plurality of open-ended jars.

29. The process of making rubber jars, comprising taking a pair of mold members, each having a pair of parallel cutting ribs thereon, seating by suction rubber stock across such ribs and in contact with the space between them, then placing within the seated stock in one of the members adjacent to the ends thereof devices which are provided with cutting edges adapted to cut both horizontally and vertically, then placing inwardly facing bottom members along the inner faces of such cutting device, placing within the seated stock one or more double bottom members, then bringing the

seated stock in the other member into conjunction with the seated stock and bottoms and cutting edges, then vulcanizing the article with the bottoms in place, then cutting 5 the vulcanized article into parts through the double bottoms and between the various bottoms to produce a plurality of open-ended jars.

30. The process of making jars of hard 10 rubber, comprising taking a pair of mold members, each having a pair of parallel ribs thereon, pneumatically seating plastic stock suitable for vulcanization into hard rubber across such ribs and in contact with the 15 space between them, then placing within the seated stock in one of the members adjacent to the ends thereof devices which are provided with cutting edges adapted to cut both horizontally and vertically, then placing 20 along the inner faces of such cutting devices bottom members having inwardly facing ribs, placing within the seated stock one or more double bottom members having ribs

on its opposite sides, then bringing the seated stock in the other member into conjunction with the seated stock and bottoms and cutting edges and causing cutting edges of the end cutters to move laterally, then transferring the closed article produced to another mold, then vulcanizing the article with 25 the bottoms in place, then cutting the vulcanized article into parts through the double bottoms and between the various bottoms to produce a plurality of open-ended hard rubber rib-bottom jars. 30

31. An apparatus of the character described comprising a pair of molds and a cooperating cutter having four rectangularly arranged cutting edges, two of them at right angles to the plane of separation of 40 the mold, and means for causing such edges to move outwardly when the molds are closed.

In testimony whereof, I hereunto affix my signature.

FRED THOMAS ROBERTS.
